UNITED STATES PATENT OFFICE.

STEELE L. THOMPSON, OF HOME, PENNSYLVANIA.

AUTOMOBILE ALARM.

1,417,700.

Specification of Letters Patent. Patented May 30, 1922.

Application filed August 6, 1921. Serial No. 490,409.

To all whom it may concern:

Be it known that I, STEELE L. THOMPSON, a citizen of the United States, residing in the city of Home and State of Pennsylvania, have invented new and useful Improvements 5 in Automobile Alarms, of which the following is a specification, reference being had to the accompanying drawings.

This invention is an automobile horn, and 10 the object is to provide a simple and efficient alarm for attachment to any one of the spark plug sockets of the internal combustion engine used upon the automobile, same to be operated by a wire extended to the dash of 15 the car.

The figure is a longitudinal, vertical sectional view through the device as attached to the engine.

The invention consists in mounting in a 20 spark plug socket 1 of the engine 2, a pipe plug 3 having a branch pipe 4 leading into one side, while the open end 5 is screw threaded interiorly to receive the spark plug 6. From the branch 4 is extended tubular 25 joints or connections such as represented at 7, 8, 9, leading to a cup or well 10. A rotary valve 11, is interposed in the joint 7, and is controlled by a wire 12 extended from the valve crank 13 to the dash. The valve 11 is 30 normally held in closed position by a spring 14. A vibrating membrane 15 is mounted in the joint 9. The well 10 is provided with drain cocks 16 and 17 and water is poured into the cup through the port 18.

When the wire is pulled the valve 11 is 35 opened, admitting gases from the engine cylinder through the device and vibrating the membrane 16, thus sounding the alarm. The water in the well 10 imparts a warbling or siren effect to the alarm. 40

While I have herein described a certain specific method of constructing and assembling the elements of my invention, it is understood same may be varied in minor details, not departing from the spirit of my 45 invention as defined in the appended claim.

I claim:

In combination with a spark plug socket of an automobile engine of the internal combustion type; an alarm for the automobile, 50 same comprising a pipe plug for seating in the socket, the outer end thereof being adapted to receive a spark plug in ordinary manner, and the said pipe plug having a branch pipe extended from one side; pipe 55 joints extended from the branch pipe; a water well at the end of the connected joints for imparting a siren effect to the alarm, said well having drain cocks and a water port for filling and emptying the well; a rotary valve 60 set in the pipe line and normally held closed; means extended to the dash for opening said valve; and a vibrating membrane set in the pipe line.

STEELE L. THOMPSON.
